UNITED STATES PATENT OFFICE.

ALEXANDER WINTON, OF LAKewood, OHIO.

INTERNAL-COMBUSTION MOTOR.

1,293,601.

Specification of Letters Patent.

Patented Feb. 4, 1919.

Application filed April 26, 1915. Serial No. 23,863.

To all whom it may concern:

Be it known that I, ALEXANDER WINTON, a citizen of the United States, residing at Lakewood, in the county of Cuyahoga and State of Ohio, have invented certain new and useful Improvements in Internal-Combustion Motors, of which the following is a specification.

This invention relates generally to improvements in internal combustion motors and particularly to that type using fuel oil. More specifically the invention relates to an internal combustion motor preferably comprising a plurality of cylinders each provided with a fuel inlet valve, pump mechanism comprising an individual pump for each cylinder, and a drip valve arranged in the line between each fuel pump and the corresponding fuel valve, whereby the operator may determine whether the several pumps are operated.

The invention may be further briefly summarized as consisting in the construction and combination of parts hereinafter set forth in the following description, drawings and claims.

Referring to the drawings, Figure 1 is a side elevation of a portion of a motor provided with my device; Fig. 2 is a view partly in section and partly in elevation of the fuel pump mechanism; Fig. 3 is a view partly in cross section and partly in elevation showing the drive for the pumps and the pump fuel supply control; Fig. 4 is a detail sectional view through the valve mechanism and the plunger of one of the pumps; Fig. 5 is a detail view of one of the fuel valves; Fig. 6 is a vertical section through the drip valve and Fig. 7 is a top plan view.

In carrying out the invention any preferred form and construction of engine and parts may be employed, but I have shown one form which meets the requirements, and in such embodiment 1 represents a portion 45 of an engine crank case connected to and supporting cylinders 3. Each of these cylinders is provided with a head 4 having an opening 5 therein for the fuel valve mechanism. The fuel valve mechanism, as set forth in Fig. 5, comprises a cylindrical valve casing 6 provided at its upper end with a flange 7 having an air connection 8 at one point and a fuel connection 9 at another point. The casing 6 is provided centrally 55 with an opening 10 extending longitudinally through the same and reduced at 11 to form

a guide for the valve stem to be described. This opening 10 below the reduced portion 11 is connected by a port 12, shown in dotted lines in Fig. 5, with the air connection 8, this air connection being in turn connected with a suitable air supply, not shown. The casing 6 is also provided centrally with an air and fuel mingling chamber 13 in communication with the opening 10, and this chamber merges into a larger recess 14, the wall of which is threaded as shown. The casing 6 is still further provided with a longitudinally disposed fuel port 15 connected by a port 16 with the fuel connection 9 at the upper end, and by a port 17 with the mingling chamber 13. Mounted within the mingling chamber 13 is a mingling block 18 having a peripheral groove 19 in alignment with the port 17, a central opening 20 forming a continuation of the opening 10 and diagonally disposed ports 21 connecting the opening 20 with the peripheral groove 19. This mingling block is held in place by a plug 22 threaded into the recess 14 and having a centrally disposed mixing chamber 23 enlarged at 24 to receive the lower end of the mingling block. This plug holds the mingling block in place, and the mixing chamber 23 receives mixing cups, 85 each comprising a cylindrical portion 25 and an inwardly extending flange 26 provided with opening 27 therein. The mixing chamber is reduced near the outer end of the plug and is provided with a valve seat 28 adapted 90 for engagement by a valve 29 arranged upon a valve stem 30 which extends through the openings in the flanges 26, through the mingling block, through the opening 10 in guide 11, and through a suitable stuffing box structure 31 arranged above the flange 7. This stem is provided with an annular groove 32 adapted to receive a split ring 33 engaging in a thrust washer 34 adapted to be engaged by a spring 35 to hold the valve 29 seated. 95 The valve stem 30 is provided with a hardened steel cap 36 adapted to be engaged by a suitable screw 37 held in the outer end of a rocker lever 38 supported upon a bracket 39 secured to the frame. The opposite end of the lever 38 is provided with a friction roller 40 engaging a cam 41 mounted upon the cam shaft 42 or any other revolving part properly timed with respect to the cycle of operations of the engine.

In operation the fuel is forced to the fuel supply port 15 by pump mechanism, to be

described, and air under pressure is supplied to the central opening 10. When the valve 29 opens, air under pressure blows through the mingling and mixing devices 5 and sprays the fuel into the cylinder, where, when the proper compression is reached, the fuel ignites and combustion takes place.

Any suitable mechanism may be utilized for forcing the fuel to the valve mechanism, 10 but I have shown one arrangement which is giving satisfaction, and this mechanism comprises a casing 43 secured to a fixed part and provided with suitable bearings 44 and 45 which support a pump shaft 46. This 15 shaft is provided with a driven gear 47 adapted to be operated from any suitable revolving part of the engine, such for example, as the cam shaft, it being important that the pumps be properly timed so that 20 injection of fuel takes place at the proper step in the cycle of operations of the engine. The shaft 46 is provided with a plurality of eccentrics 48, one for each cylinder, and each of these eccentrics receives a strap 49 25 pivotally connected by a pin 50 with a plunger 51 arranged in the pump barrel 52 preferably formed in the casing. Each pump barrel is connected by a port 53 with a discharge port 54 having therein a plu 30 rality of check valves 55. This port 54 is connected to a suitable discharge line 56. Each port 53 is also connected to an inlet port 57 provided with a plurality of inlet check valves 58. Each of these ports 57 35 is connected by a suitable pipe 59 with the corresponding fuel supply of a controlling device, which will now be described.

Secured preferably to the end of the pump casing 43 is a controller casing 60 having a 40 bearing 61 therein for receiving the end of the pump shaft 46 and between this bearing and the bearing 45 this shaft is provided with a spiral gear 62 which meshes with a spiral gear 63 slidably mounted upon a key 45 64 and vertically disposed shaft 65. The spiral gear 63 is supported in a bearing 66 in the upper part of the casing 60 and is provided with an annular groove 67 receiving the flanges 68 of the split coupling 69 50 secured to the lower end of a rod 70 connected to a rock lever 71 engaging in a groove 72 of the governor 73 which is supported at the upper end of a suitable standard 74 and is driven in any suitable manner, not shown, from the crank shaft.

The lower end of the shaft 65 passes into and operates the controlling valve mechanism, and this mechanism consists of a main block 75 secured to the lower end of the 60 casing 60 and provided with a stuffing box 76 for receiving the shaft 65. This block is provided with an annular valve seat 77 and a centrally disposed socket 78 into which the end of the shaft 65 projects. The annular valve seat 77 is provided with a plu 65

rality of ports 79, one for each cylinder, and each port is connected by a radially disposed port 80 with a fuel supply pipe 59 leading to one of the fuel pumps, already described. Engaging the face of the annular valve seat 77 is a disk valve 81 cut away at 82 to form an opening, which, at the proper step in the cycle of operations of the engine, exposes successively the ports 79. This disk is provided with a hollow hub 83 75 keyed by means of a key 84 to the lower end of the shaft 65. Extending over the valve disk 81 is a fuel inlet casing member 85 having a supply pipe 86 connected therewith so that fuel is supplied on the underside of the valve disk 81, as shown in Fig. 2. The valve disk 81 is normally held against its seat by a ball 87 engaged by a spring 88 mounted in the inlet casing member 85.

In operation fuel under pressure is supplied to the pipe 86 with the result that at the proper time fuel is admitted to the fuel pumps successively, so that they may draw in a charge depending upon the length of 90 time that the port 79 is open, the time of opening being dependent upon the position of the gear 63; that is, assuming that the engine starts on full stroke as soon as the governor comes into action, the position of 95 the gear 63 is varied so that the relative position of the valve disk 81 and the pump stroke is varied so that shoulders forming the port 82 cut off the supply of fuel to the pumps before they have completed their 100 full stroke, with the result that their barrels will only be filled for a part of the stroke, and the varied amount of fuel thus drawn will be supplied to the engine, thus varying the speed. This entire mechanism 105 is more fully set forth in my copending application, Serial No. 5995, filed February 4, 1915.

In operating the engine, it is important at times to ascertain whether the pumps are 110 forcing fuel to the valves, and to also insure a solid line of fuel free of air bubbles to secure a uniform, dependable fuel feed under all working conditions. To accomplish this result I provide each cylinder with 115 a drip valve structure, and each of these structures comprises a drip valve casing 87 having ears 88 provided with openings 89, by which the casing may be secured to the head of the cylinder, as is shown in Fig. 1. 120 The casing is provided at the left end, as shown in Fig. 6, with a threaded opening 90 receiving a jam nut 91 holding the fuel valve supply pipe 92 in place. This pipe is in communication with a port 93 125 leading to a check valve chamber 94. This chamber is closed by a suitable plug 95 at the top, and at the bottom it communicates by a port 95' with a valve chamber 96. The check valve chamber 94 receives a ball check 130

97 which seats in the opening of the port 95' as it enters the casing 94. A valve seat 98 is provided in the casing at the junction of the port 95' and the chamber 96 for a purpose to be described. The valve chamber 96 communicates by a suitable port 99 with a fuel supply pipe 56 leading from the corresponding fuel pump. This chamber 96 merges into a larger opening 100 which receives a tubular plug 101 having a valve seat 102 at the lower end and an annular recess 103 communicating by ports 104 with a central opening having the valve seat 102. A valve body 105 is supported upon a stem 106 threaded in the plug and is adapted to engage either the seat 98 or the seat 102, as will later appear. The upper end of the valve stem is provided with a suitable operating handle 107. The annular recess 103 communicates with a port 108 extending out to the side of the drip valve casing 87, and is there connected to a drip pipe 109 by a jam nut 110.

When the engine is operating, the valve body 105 is moved upward, so that it engages the valve seat 102, thereby closing communication between the valve chamber 96 and the drip pipe 109, fuel passing from the supply 56 to the fuel valve supply pipe 92 but when it is desired to ascertain whether the corresponding pump is operating, the valve body 105 is lowered until it engages the valve seat 98, causing communication between the fuel discharge pipe 56 and the fuel valve supply pipe 92 to be closed and opening communication between the pipe 56 and the drip pipe 109. This drip pipe 109 may be led to any suitable point for inspection and not only indicates the presence or absence of fuel in the line, but also enables air or gas in the pipes to be drawn off to secure a solid fuel line. The drip valve is preferably close to the fuel inlet valve to the engine cylinder to further assist in reducing liability of air

bubbles reaching said valve and varying the effective fuel charge. The ball check serves to prevent the pressure in the cylinder from blowing back through the drip valve mechanism.

Having described my invention, I claim:— 50

1. In an internal combustion motor, a cylinder, a pump for supplying fuel thereto, a conduit leading from said pump to said cylinder and provided with an outlet, and a controlling valve structure having two positions in one of which the outlet is open and the conduit closed and in the other of which the outlet is closed and the conduit is open. 55

2. In an internal combustion motor, the combination of a series of cylinders, a series of pumps for supplying fuel to said cylinders, in timed order, common means for operating said pumps, a separate supply conduit leading from each pump to its own cylinder and provided with an independent outlet, and a valve controlling the outlet from each conduit, said valves having two positions, in one of which the outlet is open and the conduit closed and in the other of which the outlet is closed and the conduit is open. 65

3. In an internal combustion motor, the combination of a cylinder, a pump for supplying fuel thereto, a valve casing having a chamber communicating with said cylinder, 75 with said pump, and with a drip opening, a valve seat in said chamber between the fuel inlet from said pump and the fuel outlet to said cylinder, a valve seat in said chamber between the fuel inlet from said pump and 80 said drip opening, and a valve co-operating with said two valve seats.

In testimony whereof I affix my signature in presence of two witnesses.

ALEXANDER WINTON.
